UNITED STATES PATENT OFFICE.

PERRY B. WHITE, OF ROCHESTER, NEW YORK.

DESIGN FOR A WATCH-CHAIN SAFETY-CLASP.

47,446.

Specification for Design.

Patented June 8, 1915.

Application filed March 25, 1915. Serial No. 17,070. Term of patent 3½ years

To all whom it may concern:

Be it known that I, PERRY B. WHITE, a citizen of the United States, and a resident of the city of Rochester, in the county of Monroe and State of New York, have invented a new, original, and ornamental Design for a Watch-Chain Safety-Clasp, of which the following is a specification, reference being had to the accompanying drawing, forming part thereof.

Figure 1 is a perspective view of a watch

chain safety clasp, showing my new design. Fig. 2, is a rear perspective view of the device shown by Fig. 1.

I claim:

The ornamental design for a watch chain safety clasp, as shown.

PERRY B. WHITE.

Witnesses:

GEORGE T. WHITNEY,
ANNA R. MCGRATH.
